Patented Oct. 17, 1967

208,939

LIGHT DIFFUSER FOR A NIGHT LIGHT

Lawrence P. Mellyn, Gloucester, R.I., assignor to General
Electric Company, a corporation of New York

Filed Sept. 20, 1966, Ser. No. 3,928

Term of patent 14 years

(Cl. D48—20)

Fig. 1.

Fig. 4.

Fig. 2.

Fig. 3.

FIG. 1 is a top plan view of a light diffuser embodying my new design;

FIG. 2 is a front elevational view thereof;

FIG. 3 is a bottom plan view thereof;

FIG. 4 is a side elevational view thereof;

FIG. 5 is a back elevational view thereof;

FIG. 6 is a front perspective view thereof; and

FIG. 7 is a back perspective view thereof.

The broken line showing of a night light base in FIGS. 6 and 7 is for illustrative purposes only.

I claim:

The ornamental design for a light diffuser for a night light, as shown and described.
